CLAIM

The ornamental design for the front portion of an automobile,
as shown and described.

DESCRIPTION

FIG. 1 is a front left perspective view of a front portion of an automobile showing our new design;

FIG. 2 is a rear left perspective view thereof;

FIG. 3 is a front right perspective view thereof;

FIG. 4 is a rear right perspective view thereof;

FIG. 5 is a front view thereof;

FIG. 6 is a rear view thereof;

FIG. 7 is a left side elevation view thereof;

FIG. 8 is a right side elevation view thereof; and,

FIG. 9 is a top plan view thereof.

The de-emphasized and halftone portions shown in the photographs illustrate environmental structure for the automobile that forms no part of the claimed design.

1 Claim, 8 Drawing Sheets
